UNITED STATES PATENT OFFICE.

JOEL G. NORTHRUP, OF MARCELLUS FALLS, NEW YORK.

FOLDING-MACHINE.

SPECIFICATION forming part of Letters Patent No. 322,552, dated July 21, 1885.

Application filed May 29, 1884. (No model.)

To all whom it may concern:

Be it known that I, JOEL G. NORTHRUP, a citizen of the United States, residing at Marcellus Falls, in the county of Onondaga and State of New York, have invented certain new and useful Improvements in Printing and Folding Machines, of which the following is a specification, reference being had therein to the accompanying drawings.

10 The printing mechanism is double—that is to say, duplicated—one set of inking and printing devices being arranged at each end of the machine and adapted, by means of suitable guide-rollers, to receive, print, and deliver 15 the web therefrom at a point about the center of the machine into and between the feeding and severing rollers, and from thence through the folding-rollers.

20 The construction and operation of the machine will be hereinafter described, and the novel features thereof will be specifically set forth in the claims.

Referring to the drawings, Figure 1 is a plan. Figs. 2 and 3 are side elevations; Fig. 4, a 25 central vertical section. Fig. 4^a is a plan of the receiving-box and the packer-operating arm; Figs. 5 and 6, end elevations; and Figs. 7 and 8 are details, hereinafter described, of a printing and folding machine constructed in 30 accordance with my invention. Figs. 9 and 10 are diagrams of opposite sides of a severed portion of a web, showing the fold-lines therein as formed by the folding mechanism.

Like letters and figures indicate like parts 35 in all the drawings.

The moving parts of the machine may be supported in any suitable frame-work; but in this instance I have constructed and illustrated a compound frame-work—that is to say, the 40 frame comprises two sections, 1 and 2, the former adapted to support the printing mechanism and the latter the folding mechanism, and each connected to the other in such a manner as to be separable therefrom bodily, and yet 45 so that the frame-work supporting the folding mechanism is capable of receiving the product of the printing mechanism. An advantage of this construction—separable frames—is that access to the folding mechanism may be had 50 for repairing or other purposes.

The frame-work of the printing mechanism

rests directly upon that of the folding mechanism, and is secured in position by bolts 3, and along the line dividing the two sections are formed at proper places bearings for certain journals or shafts hereinafter described, which shafts, in connection with suitable tie-bars or cross-beams, serve the purpose of strengthening the frame laterally. Examples of such tie-rods are illustrated at 4 in the lower portion of the frame-work.

Section 1 of the frame-work comprises two bars or standards, 5, for impression-cylinder 6, and standards 7 for the ink-distributing rolls 8. It is also provided with standards 9 for 65 the web guide rolls 10, and adjustable brackets 11, provided with bearings for a pressure feed-roll 12, said brackets being pivoted to the cross-bar 13, (extending from the standard 9 to the standard 9,) and maintained in position 70 to cause the roll 12 to bear with greater or less force on the roll 10 by means of the bolt or screw 14, set in the bar 13 and passing through a slot, 15, in the bracket. The bar 13 is extended to serve as a support to the ink-well 75 16, which is of the usual construction, and caused to feed by means of the pawl 17, pivoted to the arm 18, mounted loosely upon the shaft of the ink-well roll, which carries a ratchet, 19, said arm being operated through 80 the medium of the connecting-link 20, pivotally secured to the arm and to a lever, 21, pivotally connected to the arm 22, pivoted to the frame-work over the cam 23, mounted upon one of the transverse shafts therein.

85 The type-beds 24 are of that class which are provided with racks 25 and lugs 26, (see dotted lines, Fig. 4,) and which are thus adapted to be operated by means of pinions 27 mounted on shafts 28, one of which shafts is directly 90 connected with the impression-cylinder gear 29 by means of the pinion 30, (see Fig. 3,) the other pinion and shaft 28 being driven by an intermediate pinion, 31, mounted on an intermediate shaft, 32, the lugs 26 riding in ways 95 33, formed in the inner surfaces of the side pieces of the frame-work. Cushioning-springs 123 are arranged at the outer ends of the ways and overcome the momentum of the forms as they change direction at that point in their 100 travel.

It will be readily understood that the type-

beds 24 are successively brought beneath the impression-cylinder 6, so as to print both sides of the web, passing over the guide-rolls to one of the impression-cylinders, from thence to 5 the other, and, finally, between the rolls 10 and 12, near the folding mechanism, which will be hereinafter described.

Such features of construction as have been 10 thus far herein described, and which are of my invention and not claimed herein, are left unclaimed by reason of their being claimed in the above-named application.

A, Fig. 4, represents the web in its passage 15 through the machine as far as can be illustrated without detriment to the clear illustration of the parts thereof. The direction of the movable parts of the machine is indicated by arrows as fully as is necessary to a clear understanding of the operation of the machine.

20 Any of the shafts of the machine may be selected as the power-shaft—for example, one of the shafts 28—and the two shafts 28 are connected to each other by gears 34, (see Fig. 1,) and each of the shafts is provided with a 25 cam, 35, in which the pin 36 rides, said pin projecting from a lever, 37, pivoted at one end to the frame-work and pivotally connected at the other with one of the ink-distributing rolls 8, by which means said roll is given a 30 longitudinal reciprocation, as is usual in inking mechanism. The cam 23 is mounted upon one end of one of the bed-operating shafts 28, and once during each revolution lifts the arm 22, and this operates the arm 21 and link 20, 35 by which means the pawl 17 is operated and a transfer-roll, 38, is carried back and forth from the ink-well roll to one of the ink-distributing rolls 8.

The pinion 30 upon shaft 28 meshes with a 40 geared cam, 39, having a single operating-point, 40, (or curvature in its track,) which, in connection with suitable levers, rock-arms, and connecting-rods of a certain relative length, location, and proportion, serve to operate all 45 the moving parts of the folding mechanism, the whole of which is timed with due regard to the delivery of the printed web from the superimposed printing mechanism.

As the web passes from between the rolls 50 10 and 11, it is guided by an apron, 41, mounted upon a tie-rod, 4, into the bite of the severing and feeding rolls 42, provided with perforating-blades 43 and 44 and with spring-fingers 45. By reference to Figs. 7 and 8 the 55 construction of the perforating and severing blades will be readily understood. In the roll having the spring-fingers there are two plates or plain blades, 44, separated from each other so as to receive the single perforating-blade 60 43, mounted in the opposite roll upon pins 46, passing through inclined slots 47 in the boxing 51 of the perforating-blade. The blade 43, when otherwise not affected, projects from its roll sufficiently to simply perforate the 65 web as it passes through the rolls—for instance, on the line 1, Fig. 9. At the completion of every other revolution of the rolls

a lever, 48, having a projection, 49, is thrown into the path of the projecting end of the perforating-blade 43, which is normally held retracted by a spring, 50, secured to the end of the roll 42. Said spring bears against the end of the perforating-blade, so as to normally hold the same partly within the roll; but the said spring also yields when the projection 49 70 comes in contact with the opposite end of the perforating-blades, and it is forced longitudinally and outwardly, the latter course being taken by reason of the inclination of the slots 47, so that at the completion of every other 75 rotation of the rolls the said perforating-blade is thrown outwardly from its roll between the two plates 44 in the opposite roll such a distance that it not only perforates, but is intended to completely sever the web at every 80 second revolution of the rolls—as for instance, on the line a, Figs. 9 and 10—so that the web in passing from a' to a, between the rolls 42, 85 is perforated on the line 1 and severed at the line a.

90 In the modified form of perforating-blade shown in Fig. 8, instead of arranging the spring 50 at the end of the roll I secure it to the boxing 51 of the perforating-blade, and instead of arranging the slots 47 in said boxing 95 they are formed in the blade 43 itself. Either of these constructions may be employed, as desired, and in both constructions the boxing is firmly seated in the roll which carries the perforating-blade.

99 In Fig. 4 the lever 48 is shown by heavy dotted lines as projecting into the path of the blade 43 and in light dotted lines as out of the path of said blade. The said lever is pivoted at 51 on the inside of the frame, and is pivotally connected to the connecting-rod 52, pivotally attached to a rock-arm, 53, rigidly mounted on the shaft 54, passing through said side frame, on the outer end of which shaft is another rock-arm, 55, provided with 105 pin and friction-roll projecting into the cam 39, so that during each revolution of the cam 39, the rock-arms are oscillated and the lever 48 is thrown into the path of the perforating-blade.

The gear 56, mounted on the shaft of one of 110 the rolls 42, is one-half the diameter of cam-gear 39. The said rolls being geared together, they must make two revolutions to one of the cam gear, whereby the perforating-blade is transformed in function to a severing-blade 115 once during every second revolution of the rolls 42.

The rolls 57 are ordinary folding-rolls, with the exception that the upper one is provided with a plain bar or blade, 58, which (by means 120 of a lever, 59, thrown into and out of the path of a projecting end of said bar) is projected from the roll while blade 43 is against it to assure a complete severance of the web along the line a after the perforating function of 125 the blade 43 has been performed. Lever 59 operates with blade or bar 58 just as lever 48 operates blade 43. The contact of blades or plates 58 and 43 with each other is intended 130

to accomplish a positive separation of the web along the previously-perforated line by reason of a slight movement of the one upon the other, which is in the nature of a rubbing 5 action. Now, the rolls 57 being one-half the diameter of the rolls 42, and geared together by the pinions 60, mounted on their shafts, the upper one of such pinions meshing directly with the gear 56, and thus indirectly with the cam-gear 39, and being one-fourth the diameter of said cam-gear, an operation of the lever 59 (through the medium of the connecting-rod 61, and rock-arm 62, mounted on the shaft 63, having the outside rock-arm 64, provided with 15 a pin projecting to the cam-groove of gear 39,) must follow at each passage of the point 40 of the gear and the lever 59 will be thrown into the path of the bar 58; and, by reason of the proportion existing in the rolls 57 and 20 their companions relative to the diameter of the cam-gear, said lever 59 will be operated once in every fourth revolution of said rolls 57, and these rolls are so timed with relation to rolls 42 that the said bar 58 will be thrown directly alongside of perforating-blade 43, which projects slightly from roll 42, so as to 25 assure the separation of the web, as before described.

A rotary brush, 65, runs in contact with one 30 of the rolls 42 and in a direction opposite to its rotation, to insure the deliverance or direction of the leading end of the web downwardly in front of the rolls 57. The brush is rotated by means of a gear, 66, which meshes 35 with severing-roll gear 67, as clearly shown in Fig. 2, there being an intermediate gear, 68, to give the brush the right direction of rotation.

The leading end of the web is carried down in front of and below the rolls 57 to such a 40 distance as is necessary to bring the line 1, Fig. 9, opposite the bite-line of said rolls, when the first fold is made along said line 1, which has been perforated as before described. The means for making the folds upon the line 1 is 45 an oscillating folding-blade pivoted on a shaft, 70, operated by means of a rock-arm, 71, (see Fig. 3,) a connecting-rod, 72, and a rock-arm, 73, loosely pivoted on a shaft, 54. Between the pivotal joint and rock-arm 73 there is piv- 50 otally connected with said rock-arm another link, 75, which carries a pin and friction-roller 76, which projects into the groove of the cam. To said pin are connected also a suspension link, 77, pivotally secured at 78 to the frame- 55 work, and a connecting-rod, 79, which is piv- 60 otally connected to a rock-arm, 80, rigidly se- cured to an upright shaft, 81, on which is mounted the rock-arms, 82, which carries the final folding-blade 83, hereinafter referred to. 65 The suspension-link serves the purpose of retaining the pin 76 against downward move- ment when it is forced in lateral directions by the point 40 of the cam; and by this combina- 70 tion and arrangement of connecting rods, 75, rock-arms, and suspension link several inde- 75 pendent devices in the folding mechanism are

in proper relative time operated by the single-pointed cam.

The folding-blade 69 is provided with spring-fingers 84, depending therefrom and 70 arranged to depress the web against a raised portion of a curved plate or bed, 85, and while so held by the fingers the web is touched by a paste-dabber, 86, (which is a piece of leather, rubber, or other suitable 75 material,) held between clamps 87, and extending a distance equal to or slightly greater than the width of the web, and mounted in rock-arms 88, mounted on a shaft, 74, and connected by a link, 89, to the arms 80 of the folding-blade. To said arms is secured a second link, 90, which is pivotally connected to an ordinary pawl and ratchet for operating a paste-roll, 91, running in a paste- 85 vat, 92, so arranged that in its oscillatory movement the paste-dabber 86 shall come in contact with the paste-roll 91 and carry paste therefrom to the web when it is held against the bed 85, as described.

The relative proportion in size of the feed- 90 ing and severing rolls 42 with the cam-gear 39 is such that the folding-blade 69 and the paste-dabber 86 are operated once and sub- 95 stantially simultaneously during every two revolutions of said rolls, so that a single line 95 of paste (on the line 2 of Fig. 9) is applied upon each severed portion of the web, so that when the fold is made on the perforated line 1 and the two portions of the web at each side of said fold-line are brought together in pass- 100 ing through the rolls 57, the said portions of the web are caused to adhere to each other along the said line 2.

As the now-folded web passes through the rolls 57, it is delivered upon a table or bed, 93, 105 having a transverse opening over the second folding-rolls, 94. An oscillating folding-blade, 95, operates in connection therewith to form a second transverse fold on the lines 2, Fig. 9. At this point the severed portion of the web 110 is folded into an eight-page paper, being se- 115 cured by paste along one fold-line, and being perforated along the other fold-line, whereby it is susceptible of severance along said first fold-line to gain access to the second and third 115 pages thereof.

The folding-blade 95 is mounted upon a shaft, 120 96, having a rock-arm, 97, on the outside of the frame, and having connecting-rod 98 pivotally connected with a rock-arm, 99, mounted on 120 the shaft 100, suitably supported in the frame- 125 work and having at its free end pin 101, project- 125 ing into the groove of cam 39. The fold- 130 ing-rolls 94 are operated by means of gears 102, meshing with an intermediate, 103, which meshes with the gears 60 of folding-rolls 57.

Now, in order to double the number of pages in the severed portion of the web, a vertical pair of folding-rolls are arranged beneath the folding-rolls 94, so that the previously-folded 130 sheet is delivered in front of, and is passed between the same by the heretofore-mentioned

folding-blade 83, the dotted line at A, Fig. 4, indicating the folded paper passing with the blade into the bite of the rolls. In making this fold in the previously-folded sheet the 5 paster 86 should be thrown out of action by disconnecting its link 89 from the folding-blade 69, and any suitable well-known paste-applying devices, 69½, may be arranged to lay a line of paste along the fold-line 3 of Fig. 9, 10 one of the rolls 42 being grooved circumferentially at 42½ to avoid contact with the said paste-line in order to bring the pasted portion of the web on the final fold-line. The folding-blade 83 folds the severed portion of the web 15 along the line 3. Paster 86 should be thrown out of action when paster 69½ is in use.

Now, it will be noticed by reference to Figs. 9 and 10 that when the last fold is made a sixteen-page paper is formed by each of the severed portions of the web produced in the manner described, the numbers at the corners of the divisions made by the folding lines of said portions, as illustrated in Fig. 9, being the page-numbers as they occur in the completely-folded portion on one side of the web, and the similarly-arranged numbers in Fig. 10 indicating the pages produced by the printing upon the opposite side of the web and the subsequent folding thereof, as described.

30 The vertical folding-rolls 104 are operated by means of pinions 105, arranged at their lower ends; and the miter-gear 106, arranged at the lower end of one of the rolls, meshes with another miter-gear (not shown) on the 35 horizontal shaft 107, (see Fig. 2,) carrying a miter-gear, 108, meshing with a companion, 109, mounted on a vertical shaft, 110, arranged outside of the frame and carrying a miter-gear, 111, meshing with a companion, 112, 40 mounted on one of the horizontal folding-rolls 94. 113 represents a receiving-box having a packer, 114, reciprocated therein by means of a bell-crank lever, 115, secured to a vertical shaft, 116, operated by means of a connecting-rod, 117, and a second bell-crank lever, 118, 45 pivoted to the frame-work and carrying a pin, 119, projecting into the groove of the cam 39. A spring, 120, (see Figs. 2 and 4,) secured to a side wall of the receiving-box, projects into the 50 box and into the path of the packer 114, so that as the packer, when reciprocated to compress the papers within the receiver, reaches a point beyond the free end of the spring, (shown in elevation in Fig. 2, and in section in Fig. 4) 55 said spring is compressed against the side wall and remains there until the return of the packer, when it immediately springs outwardly and retains the papers from following the packer in its backward movement. In front of the 60 packer is a spring-seated follower or plate, 121, extending along the side of the box 113, and bent at a right angle to extend less than the entire width of the receiving-box, as clearly shown in elevation in Fig. 2 and in section in 65 Fig. 4. The coiled spring 122 is housed in the recess formed at the side of the receiving-box,

and secured at one end to a portion of the retaining-plate 121, and at the other end to a wall of the recess, so that when it is desired to remove papers from the receiving-box the 70 said plate may be drawn toward the side of the machine and against the tension of the spring with one hand, while the papers are removed from the box with the other.

Instead of dividing the two sections of the 75 frame along a line which necessitates the forming of half-boxes in each section for the shafts 27 and 28, the upper section may be depressed, as shown in Fig. 2, at the line 124, where said shafts pass through, so that whole bearings 80 for said shafts shall be in the upper section. Various other changes in the outline of the joining portions of the two frames may be made, and yet secure the advantage of bodily separation of the printing mechanism from the 85 folding mechanism.

By using properly-proportioned gearing, the rolls 57 may be one-third the diameter of rolls 42, and other changes in proportion of the rolls and cam-gear, arms and levers may 90 be made, if desired; and, furthermore, a single set of printing devices may be employed with the folding devices, or the printing and folding mechanism may be used separately.

A companion application, No. 133,592, 95 discloses some of the features herein shown and described and not claimed, and having particular relation to a modified construction of the frame-work and means for moving the beds therein, and other features herein shown and 100 not claimed are shown in my patent No. 305,469, having reference to the same devices and mechanism for operating them in connection with the impression-cylinder.

Having described my invention and its operation, what I claim is—

1. The combination, with printing mechanism, substantially as described, of severing-rolls, as 42, an intermediate guiding-apron, as 41, folding-rolls, as 57, and an oscillating folding-blade, as 69, provided with depending spring-fingers, as 84, and a curved bed, as 85, substantially as shown and described.

2. The rolls 42, one of which is provided with a longitudinally-reciprocating perforating-blade, 43, the other of which is provided with two stationary plates, as 44, in combination with the pivoted lever 48, having the projection 49, the connecting-bar 52, the rock-arms 53 and 55, and the gear-cam 39 and gear 56, whereby the said projection 49 is brought into the path of the perforating-blade 43 once during every two revolutions of the said rolls to change the function of the perforating-blade to that of a severing-blade, substantially as specified.

3. The combination of the rolls 42, one of which is provided with a perforating-blade, as 43, with the folding-rolls 57, one of which is provided with a plain blade adapted for longitudinal movement, and with a lever, 59, connecting-rod 61, rock-arms 62 and 64, cam-

gear 39, and gears 56 and 60, substantially as and for the purpose set forth.

4. The combination, with the rolls 42, having the blades 43 44, the rolls 57, one of them 5 having the blade 58, the levers 48 and 59, the rotary brush 65, and means, constructed, arranged, and timed, substantially as shown and described, for operating the same, substantially as and for the purpose set forth.

10 5. The combination of the rolls 57, folding-blade 69, having depending fingers 84, the curved bed 85, the paster 86, mounted upon arms 88, the connecting-links 89 90, and the paste-roll 91, with means, substantially as 15 shown and described, for their operation, substantially as and for the purpose set forth.

6. The combination of the vertical folding-rolls 104, folding-blade 83, and the packing-box 113, having a side spring, 120, a reciprocating packer, 114, and a spring-actuated compressing-plate, 121, substantially as shown 20 and described.

7. The combination, with the oppositely-arranged impression-cylinders 6 and their adjacent inking mechanism, of the oppositely- 25 arranged series of forms and their operating devices, comprising the shafts 28 and gears 34, with gear 29, pinion 30, and cam-gear 39, provided with a single operating-point, 40, and with the rock-arms 55, 64, 75, and 99, 30 and bell-crank lever 119, the feeding-rolls 42, and folding-rolls 57, 94, and 104, the folding-blades 69, 95, and 83, and pivoted levers 48 and 59, and the connecting-rods connecting 35 said blades and levers with said arms, whereby the entire folding apparatus is operated by a single cam having connection with an impression-cylinder, substantially as specified.

In testimony whereof I affix my signature in presence of two witnesses.

JOEL G. NORTHRUP.
